Primary Examiner — Rhea Shields(74) *Attorney, Agent, or Firm* — Faegre Drinker Biddle & Reath LLP(57) **CLAIM**

The ornamental design for a medical equipment cart, as shown and described.

DESCRIPTION

FIG. 1 is a front perspective view of medical equipment cart illustrating our new design;

FIG. 2 is a front side view of our new design;

FIG. 3 is a back side view of our new design;

FIG. 4 is a left side view of our new design;

FIG. 5 is a right side view of our new design;

FIG. 6 is a top view of our new design; and,

FIG. 7 is a bottom view of our new design.

In the drawings, the evenly-sized broken lines are for the purpose of illustrating environment only and form no part of the claimed design. The long-short broken lines are for the purpose of illustrating boundaries of the claim and form no part of the claimed design.

1 Claim, 7 Drawing Sheets(56)
